BURNER FOR LIQUID AND GASEOUS FUELS

Kurt Hugo Folke Lundberg and Karl Einar Lundberg, Uppsala, Sweden

Application December 22, 1949, Serial No. 134,452
In Sweden February 1, 1949

7 Claims. (Cl. 299—117)

1

The present invention relates to burners for liquid and gaseous fuels of the type comprising a casing forming an air chamber and provided with an air inlet and with an axially disposed air outlet, in which casing there is axially arranged a tubular fuel supply member provided with a nozzle through which the fuel is adapted to be discharged and which serves also as a valve for the air outlet, being movable towards and away from the latter.

An object of the invention is to provide a burner of this type which permits the length and configuration of the flame to be altered within wide limits.

Another object is to provide a burner of the type indicated wherein the air blast issuing through the axial air outlet may be set in controllable rotating or swirling motion in any adjusted position of the combined fuel nozzle and valve member relatively to the air outlet.

A further object is to provide a burner of the type indicated wherein the rotating or swirling motion of the issuing air blast is brought about by means of guide plates which are displaceably mounted in longitudinal and obliquely disposed slots in said nozzle and valve member and which may be caused to project a desired distance from said member into the space between the same and the surrounding inner wall of the burner casing so as to form in this space a series of tangentially disposed channels through which the air is set in rotating or swirling motion of desired intensity.

Further objects of the invention will appear from the following description of a preferred embodiment of the burner shown in the accompanying drawing, wherein:

Fig. 1 is a longitudinal sectional view of the burner.

Fig. 2 is a cross sectional view on line II—II of Fig. 1.

Fig. 3 is a cross sectional view on line III—III of Fig. 1.

Fig. 4 is a longitudinal sectional view of the front portion of the burner, the details being shown in another position than in Fig. 1.

Fig. 5 is a front view of the combined nozzle and valve member.

Fig. 6 is a longitudinal sectional view taken on line VI—VI of Fig. 3 through the rear portion of a central tubular member and of sleeves surrounding the same and illustrates more in detail a mechanism for independently moving these sleeves.

Referring to the drawing numeral 1 designates a tubular casing having a lateral inlet 2 for com-

2

pressed air and a contracted outlet portion indicated by 3. At its rear end the casing is closed by means of a cap shaped member 4, which is removably connected to the casing by means of screws 5. A tubular member 6 extends centrally through the burner casing 1 and is removably fixed to the cap 4 at its rear end. For such purpose this rear end is formed as a double cone 7, one conical surface of which engages a conical seat 8 provided in the cap 4, whereas its other conical surface engages a conical seat 9 provided in a rear valve section or casing 10. A nut 11 is turnably but not displaceably mounted on the threaded end portion of the cap 4, a tightening of the nut bringing about the required centering of and tightening between the interconnected parts 4, 7 and 10.

The front portion of the tubular member 6 terminates at some distance behind the front end of the burner casing 1. On the central tubular member 6 there is displaceably mounted a sleeve 12 to the front end of which a fuel nozzle and valve member 13 is rigidly secured. In the embodiment shown in Fig. 1 this fuel nozzle and valve member has the shape of a frustum of a double cone. The inner wall of the outlet portion 3 of the burner casing 1 is in the form of a hollow cone 3' (Fig. 4) of somewhat greater cone angle than the conical front surface 13' of the nozzle and valve member. Fig. 1 shows the valve member 13 when advanced as much as possible so as to close the air outlet 3 of the burner casing. From this foremost position the valve member 13 may be retracted so as to form an annular slot of adjustable width between the outlet 3 of the burner casing and the valve member through which slot an air blast may issue from the interior of the burner casing. The conical inner surface 3' of the outlet portion 3 is followed by a cylindrical surface 14. In the valve member 13 three equidistantly spaced pins 15 are secured, the outer ends of these pins being adapted to slide on said cylindrical surface, thus guiding and centering the combined nozzle and valve member when the same is moved.

At its front end the tubular member 6 has a narrow cylindrical extension 16 through which the fuel channel 17 also extends. This cylindrical extension engages in a corresponding bore 18 in the nozzle and valve member 13. The bore 18 opens at the front end of the nozzle and valve member in a number of fine diverging ducts 19, which in turn open into an annular groove 20 provided in the outer end face of the nozzle and

valve member 13. The number of fuel ducts 19 may vary. In the embodiment shown four such symmetrically disposed ducts are provided (see Fig. 5).

The combined nozzle and valve member 13 is provided with a number of longitudinally extending slots 21 spaced equidistantly around the same (Fig. 5). The slots 21 are made in planes parallel to but not intersecting the axis of the nozzle and valve member. In the slots 21 plates 22 are displaceably arranged, these plates at their rear ends being secured in an annular member 23 which has a rearward sleeve shaped extension 24 displaceably mounted on the sleeve 12 carrying the nozzle and valve member 13. A resilient ring 25 is mounted around the plates 22. This ring 25 exerts a radial pressure upon the plates 22 and serves to keep the same in the slot 21 with the inner edge of each plate 22 abutting against the bottom of its slot.

As will be understood from the above description, the valve member 13 and the plates 22, respectively, are individually displaceable relatively to the air outlet 3 of the burner casing. In all positions of the valve member 13 relatively to said air outlet the plates 22 may be retracted within the valve member or caused to project any distance from the same for the purpose of forming thereon more or less deep, tangentially disposed channels through which the issuing air blast is set in rotating or swirling motion.

At its rear end each of the two sleeves 12 and 24 terminates in a semi-cylindrical portion 26 and 27, respectively, said portions surrounding the tubular member 6 and being slidable thereon (Fig. 3). These semi-cylindrical portions are formed as racks and each rack engages with a toothed shaft 28 and 29, respectively, which extends outwardly through a stuffing box 30 and 31, respectively, provided in the wall of the burner casing. At its outer end each shaft 28 and 29 carries a hand wheel 32 and 33, respectively, provided with a pointer 34 and 35, respectively, which cooperates with a dial 36 and 37, respectively. By means of these hand wheels the valve member 13 and the plates 22 may be adjusted independently of one another. From Fig. 6 it appears more clearly that a portion of the sleeve 12 is cut away at the rear end thereof as from line 12' leaving the semi-cylindrical extension 26 which is toothed as at 52 for cooperation with the toothed shaft 28, and that portion of the sleeve 24 is likewise cut away at the rear end thereof as from line 24' leaving the semi-cylindrical extension 27 which is toothed as at 53 for cooperation with the toothed shaft 29. Rotation of shaft 28 causes the sleeve 12 to be moved longitudinally independently of the sleeve 24, and rotation of shaft 29 causes the sleeve 24 to be moved longitudinally independently of the sleeve 12.

The valve section 10 has an axial bore 38 communicating with the fuel channel 17 of the tubular member 6. A radial bore 39 opens into the axial bore 38 and is intended to be connected to a conduit for supplying fuel under pressure to the burner. The flow of fuel is controlled by means of a threaded needle valve 40 which is coaxial with the bore 38, the spindle of the said valve extending outwardly through a stuffing box 41 provided in the casing and carrying at its outer end a hand wheel 42 with a pointer 43 cooperating with a dial 44.

Adjacent its rear end the tubular member 6 is provided with a short radial channel 45 which

communicates with a channel 46 extending longitudinally through the cone shaped portion 7. At the rear opening of the channel 46 there is provided an annular groove 37 in the conical surface, said groove communicating with a longitudinal channel 48 in the valve casing 10. The channel 48 communicates with the central bore 38 through a short radial channel 49 opening in front of the needle valve 40. The radial channel 49 may be closed by means of a threaded needle valve 50 provided with a hand wheel 51.

The operation of the device now described is as follows.

In Fig. 1 the fuel control valve 40 is shown in closed position and the conical valve member 13 is shown as advanced to a position in which it closes the air outlet at the front end of the burner casing 1. When it is desired to start the operation of the burner the valve member 13 is somewhat retracted so that there will be formed a narrow annular slot, through which an air blast issues. The fuel control valve 40 is also opened so as to cause fuel (oil or gas) to be discharged through the nozzle ducts 19 in a suitable quantity. The mixture of fuel and air thus formed is ignited. The flame may then be adjusted by means of the three hand wheels 42, 32 and 33 controlling fuel supply, air supply and intensity of rotation of the issuing air blast, respectively.

After the hand wheel 42 controlling the fuel supply has been adjusted so as to cause a suitable fuel quantity to be discharged and the hand wheel 32 controlling the air supply has been adjusted to emit a corresponding amount of air which means that the valve member 13 has been withdrawn a suitable distance from the position shown in Fig. 1 so as to form an annular air discharge slot of suitable size, it is possible by turning the hand wheel 33 to adjust the intensity of rotation of the issuing air blast between zero and a maximum value. If the guide plates 22 are entirely withdrawn within the valve member 13, a free or unobstructed conical passage is formed between the valve member 13 and the inner wall of the outlet portion 3 of the burner casing, through which passage the air issues in an essentially linear flow (zero rotation). In this case a relatively contracted flame of great length is obtained. By turning the hand wheel 33 in the direction to cause the guide plates 22 to be projected more or less from the conical front surface of the valve member 13 there are formed thereon tangentially disposed channels of adjustable depth which impart a rotating or swirling motion to the issuing air. The more the guide plates 22 are advanced, the more intense this swirling motion will be. Maximum rotation of the air blast is obtained when the guide plates have been caused to project as far as possible, i. e. when their front ends, which are conformed to the profile of the inner wall of the outlet portion 3, abut against this wall. In this position practically the entire space between the valve member 13 and the outlet portion 3 of the burner casing is divided into channels by the guide plates 22, said channels guiding the air and imparting a rotating or swirling motion to the same. When the rotation of the air is increased, the length of the flame is diminished, the flame finally assuming the shape of a slightly conical disc close to the burner outlet.

By way of example Fig. 4 shows the valve member 13 when withdrawn to its extreme rear position and the guide plates 22 projecting from the valve member 13 to such extent that the main

portion of the conical passage between the valve member and the outlet portion 3 of the burner casing is divided into channels which impart a rotating or swirling motion to the air blast.

When it is desired to clean the fuel channels 17, 19 in the tubular fuel supply member 6 and nozzle member 13 the fuel control valve 40 and the axial air outlet from the burner casing are closed and the needle valve 50 is opened whereby an air blast will pass from the air chamber through the ducts 45, 46, 47, 48 and 49 to the rear end of the fuel channel 17 and from thence outwardly through the channel 17 and the ducts 19.

Various modifications of the burner as described above are conceivable within the scope of the invention as defined by the appended claims. Thus, the conicity of the surface 3' and 13' may vary, and the surface 3', i. e. the portion of the inner wall of the burner casing which is closest to the air outlet, may even assume the shape of a plane surface extending perpendicularly to the axis of the burner casing. Instead of being conical the valve member 13 may have any other suitable form. Thus, the same may be formed as a segment of a sphere, an ellipsoid, paraboloid, hyperboloid etc.

What we claim is:

1. In a burner for liquid and gaseous fuels, a casing forming an air chamber and provided with an air inlet and with an axial air outlet, a tubular fuel supply member extending axially through said casing in spaced relation to the same and terminating adjacent said air outlet, a nozzle member mounted on said tubular fuel supply member, through which nozzle member the fuel is adapted to be discharged, said nozzle member serving also as a valve for the air outlet and being movable in axial direction towards and away from the same for controlling the amount of air issuing therethrough, the nozzle member being provided with a number of longitudinally extending oblique slots, a series of guide plates displaceably mounted in said slots, and means associated with said burner casing for independently moving said guide plates axially relatively to said nozzle member so as to permit the guide plates to be retracted into and caused to project from the nozzle member in various positions of the latter relatively to the air outlet so as to divide the space between the nozzle member and the surrounding inner wall of the burner casing into a series of tangentially disposed air channels of a depth corresponding to the length of the projection portions of the guide plates and by which the air blast issuing through the air outlet and mixing with the discharged fuel is set in controllable swirling motion permitting the length and configuration of the flame to be altered within wide limits.

2. In a burner for liquid and gaseous fuels, a casing forming an air chamber and provided with an air inlet and with a tapering axial air outlet, a tubular fuel supply member extending axially through said casing in spaced relation to the same and terminating behind said air outlet, a tapering nozzle member mounted on the front end of said tubular fuel supply member, through which nozzle member the fuel is adapted to be discharged, said nozzle member being movable in axial direction towards and away from said air outlet and serving as a valve for controlling the amount of air issuing therethrough, the nozzle member being provided with a number of longitudinally extending oblique slots, a series

of guide plates displaceably mounted in said slots, and means associated with said burner casing for independently moving said guide plates relatively to said nozzle member so as to permit the guide plates to be retracted into and caused to project from the nozzle member in various positions of the latter relatively to the air outlet so as to divide the space between the nozzle member and the surrounding inner wall of the burner casing into a series of tangentially disposed air channels of a depth corresponding to the length of the projection portions of the guide plates and by which the air blast issuing through the air outlet and mixing with the discharged fuel is set in controllable swirling motion permitting the length and configuration of the flame to be altered within wide limits.

3. In a burner for liquid and gaseous fuels, a tubular casing forming an air chamber and provided with a lateral air inlet and with an axially disposed air outlet, a fixed tubular fuel supply member extending axially through said casing in spaced relation to the same and terminating behind said air outlet, a first sleeve displaceably mounted on said tubular supply member, a fuel nozzle secured to the front end of said sleeve and being movable therewith towards and away from said air outlet to serve also as a valve for controlling the amount of air issuing therethrough, said fuel nozzle being provided with a number of circumferentially spaced oblique longitudinally extending slots, a second sleeve concentric with said first sleeve and displaceably mounted thereon, a series of guide plates slidably arranged within the slots of the fuel nozzle and connected to said second sleeve, and means for independently moving said two sleeves axially for adjusting the position of the fuel nozzle relatively to the air outlet to control the amount of air issuing therethrough and for causing the guide plates to project from said fuel nozzle a desired distance so as to form in the space between said fuel nozzle and the surrounding inner wall of the burner casing a series of tangentially disposed air channels of adjustable depth by which the air blast issuing through the air outlet and mixing with the discharged fuel is set in controllable swirling motion permitting the length and configuration of the flame to be altered within wide limits.

4. In a burner for liquid and gaseous fuels, a tubular casing forming an air chamber and comprising a tubular front section provided with a lateral air inlet and with an axially disposed air outlet, and a rear cap shaped section removably connected to said tubular front section and provided in its end face with an axially disposed conical seat, a valve section removably connected to the rear end of said cap shaped section and provided with a conical seat facing the conical seat of the cap shaped portion and with a fuel duct and a valve for controlling the flow of fuel therethrough, a tubular member extending through said casing in spaced relation to the same and formed at its rear end with a double conical portion seated in the aforesaid two conical seats and clamped between the same, the duct of said tubular member communicating with the fuel duct in said valve section, a first sleeve displaceably mounted on said tubular fuel supply member, a fuel nozzle secured to the front end of said sleeve and being movable therewith towards and away from said air outlet to serve also as a valve for controlling the amount of air issuing therethrough, said fuel nozzle being pro-

vided with a number of circumferentially spaced oblique longitudinally extending slots, a second sleeve concentric with said first sleeve and displaceably mounted thereon, a series of guide plates slidably arranged within the slots of the fuel nozzle and connected to said second sleeve, and means for independently moving said two sleeves axially for adjusting the position of the fuel nozzle relatively to the air outlet to control the amount of air issuing therethrough and for causing the guide plates to project from said fuel nozzle a desired distance so as to form in the space between said fuel nozzle and the surrounding inner wall of the burner casing a series of tangentially disposed air channels of adjustable depth by which the air blast issuing through the air outlet and mixing with the discharged fuel is set in controllable swirling motion permitting the length and configuration of the flame to be altered within wide limits.

5. In a burner for liquid and gaseous fuels, a tubular casing provided with an air inlet and with a contracted axial air outlet portion having a conical inner surface, a tubular fuel supply member extending axially through said casing in spaced relation to the same and terminating behind said air outlet, a conical nozzle member through which the fuel is adapted to be discharged mounted on said tubular fuel supply member, said nozzle member having a cone angle which is less than the cone angle of the conical inner surface of the outlet portion of the casing and being movable in axial direction towards and away from the air outlet to serve as a valve for controlling the amount of air issuing therethrough, the nozzle member being provided with a number of longitudinally extending oblique slots, a series of guide plates having their front ends conformed to the inner conical shape of said outlet portion of the burner casing slidably mounted in said slots, and means associated with said burner casing for independently moving said guide plates axially relatively to said nozzle member so as to permit the guide plates to be retracted into and caused to project from the nozzle member in various positions of the latter relatively to the air outlet so as to divide the space between the nozzle member and the surrounding inner wall of the burner casing into a series of tangentially disposed air channels of a depth corresponding to the length of the projecting portions of said guide plates and by which the air blast issuing through the air outlet and mixing with the discharged fuel is set in controllable swirling motion permitting the length and configuration of the flame to be altered within wide limits.

6. In a burner for liquid and gaseous fuels, a tubular casing forming an air chamber and provided with a lateral air inlet and with an axially disposed air outlet, a fixed tubular fuel supply member extending axially through said casing in spaced relation to the same and terminating behind said air outlet, a first sleeve displaceably mounted on said tubular fuel supply member, a fuel nozzle secured to the front end of said sleeve and being movable therewith towards and away from said air outlet to serve also as a valve for controlling the amount of air issuing therethrough, said fuel nozzle being provided with a number of circumferentially spaced oblique longitudinally extending slots, a second sleeve concentric with said first sleeve and displaceably mounted thereon, a series of guide plates slidably arranged within the slots of the fuel nozzle and

connected to said second sleeve, part of each of said sleeves being formed as a rack, and means including a toothed shaft extending through the wall of the burner casing and engaging the rack portion of each sleeve for independently moving the same axially for adjusting the position of the fuel nozzle relatively to the air outlet to control the amount of air issuing therethrough and for causing the guide plates to project from said fuel nozzle a desired distance so as to form in the space between said fuel nozzle and the surrounding inner wall of the burner casing a series of tangentially disposed air channels of adjustable depth by which the air blast issuing through the air outlet and mixing with the discharged fuel is set in controllable swirling motion permitting the length and configuration of the flame to be altered within wide limits.

7. In a burner for liquid and gaseous fuels, a casing forming an air chamber and provided with an air inlet and with an axial air outlet, a tubular fuel supply member extending axially through said casing in spaced relation to the same and terminating adjacent said air outlet, a nozzle member mounted on said tubular fuel supply member, through which nozzle member the fuel is adapted to be discharged, said nozzle member serving also as a valve for the air outlet and being movable in axial direction towards and away from the same for controlling the amount of air issuing therethrough, the nozzle member being provided with a number of longitudinally extending oblique slots, a series of guide plates displaceably mounted in said slots, means associated with said burner casing for independently moving said guide plates axially relatively to said nozzle member so as to permit the guide plates to be retracted into and caused to project from the nozzle member in various positions of the latter relatively to the air outlet so as to divide the space between the nozzle member and the surrounding inner wall of the burner casing into a series of tangentially disposed air channels of a depth corresponding to the length of the projection portions of said guide plates and by which the air blast issuing through the air outlet and mixing with the discharged fuel is set in controllable swirling motion permitting the length and configuration of the flame to be altered within wide limits, and means including a valve controlled duct extending at least in part through said tubular fuel supply member and connecting said air chamber with the rear end of the fuel channel in said tubular fuel supply member for the purpose of permitting cleaning of the fuel channel by means of an air blast.
